[57] **CLAIM**

The ornamental design for a bait bucket, as shown and described.

DESCRIPTION

FIG. 1 is a perspective view of a bait bucket showing our new design;

FIG. 2 is a top plan view thereof;

FIG. 3 is a front elevational view thereof, the rear view being a mirror image of that shown; and,

FIG. 4 is a right side elevational view thereof, the left side view being a mirror image of that shown.

The bottom surface of the bait bucket is not part of the design sought to be patented and is therefore not shown. The portion of the bait bucket shown in broken lines is not part of the design sought to be patented.
